(57) **CLAIM**

The ornamental design for the chain hook assembly, as shown and described herein.

DESCRIPTION

FIG. 1 is a perspective left, bottom view of the chain hook assembly in accordance with our invention;

FIG. 2 is a left side view thereof;

FIG. 3 is a right side view thereof;

FIG. 4 is a front view thereof;

FIG. 5 is a back view thereof;

FIG. 6 is a bottom view thereof; and,

FIG. 7 is a top view thereof.

The broken line portion of the figure drawings is included to show portions of the article that form no part of the claimed design.

1 Claim, 3 Drawing Sheets
